T. A. HUTSELL

PISTON RING EXPANDER

Filed Sept. 1, 1923

Thomas A. Hutsell Inventor

Attorney

UNITED STATES PATENT OFFICE.

THOMAS A. HUTSELL, OF SPOKANE, WASHINGTON.

PISTON-RING EXPANDER.

Application filed September 1, 1923. Serial No. 660,625.

To all whom it may concern:

Be it known that I, THOMAS A. HUTSELL, a citizen of the United States, residing at Spokane, in Spokane County and State of Washington, have invented certain new and useful improvements in Piston-Ring Expanders, of which the following is a specification.

The present invention relates to improvements in piston ring expanders designed especially for hand manipulation and of the plier type.

As is well known the rings for use with pistons for internal combustion engines, which are accurately machined and true before being applied to the piston grooves, are in many instances badly distorted, twisted or sprung during the process of expansion for application to the piston, with consequent loss of efficiency in the performance of their functions. A frequent cause for this distortion is due to lack of uniformity and equal distribution of the power applied by an implement employed in expanding the ring. By the utilization of my invention the ring may be expanded with facility and accuracy, slipped over the piston and then released to snap into position without undue or excessive strains, thus permitting the ring to assume its operative position in its original and normal condition.

The invention consists in certain novel combinations and arrangements of parts involving an implement of the plier type whereby the ring may be gripped and subsequently expanded by one continuous compression movement of the plier-handles; in which the released handles are separated by a spring; and in which the released jaws are also separated by spring actuated movement, as will be hereinafter more fully described and claimed.

In the accompanying drawings I have illustrated one complete example of the physical embodiment of my invention wherein the parts are combined and arranged in accordance with the best mode I have thus far devised for the practical application of the principles of my invention.

Figure 1 is a top plan view of the implement shown in normal position in full lines and applied to a piston ring, and in dotted lines shown in position after expanding the ring.

Figure 2 is an edge view of the implement. Figure 3 is a detail perspective view of

one of a pair of handles of the plier type for spreading or expanding the ring.

Figure 4 is a detail view of one of the links between a handle and gripping or relatively movable jaw.

Figure 5 is a perspective view of one of the stationary jaws.

Figure 6 is a perspective view of one of the relatively movable, pivoted jaws.

The two handles 1 and 2 of the plier type are fashioned in suitable shape from metal blanks and provided with angularly disposed, integral arms 3 and 4. The handles are associated and pivoted together as by a pin 5, and are designed to be compressed or drawn together by hand-grip as indicated in dotted lines Figure 1. On the pivot pin 5 and above the two pivoted handles are retained a pair of pivoted arms 6 and 7, each of which is fashioned from a metal blank that is twisted or turned as indicated in Figure 5 to form a relatively stationary jaw member as 8 and 9. Thus the arms at their pivot ends lie in a horizontal plane and the jaws formed integral with the arms are disposed in a plane at right angles to that of the arms. The arms are capable of a pivotal movement on the pin 5 in a horizontal plane, but the jaws, which of course move with the arms while the two ends R and R' are being separated, do not move in a vertical direction in their function of gripping the ring ends. Each of the jaws has a tooth 10 which is designed to fit up under the outer edge of the ring, but as indicated in Figure 1 these jaws do not extend the full width of the ring. The two jaw members are normally held together by means of a spring 11 located between them with its ends secured in the holes 12 therein, and the jaws are returned by the spring to normal position, after release, after having spread the ring ends R and R', a stop lug 13 being provided on the arm 6 for co-action with the arm 7 as indicated in Figure 1 to limit the movement of the jaws under tension of the spring.

Each of the stationary jaws has for co-action therewith a relatively movable jaw as 14 and 15 and these jaws each has a tooth 16 integral therewith to bear upon the upper outer edge of the ring ends above the complementary teeth 10 of the stationary jaws. These movable jaws have a pivotal movement on the stationary jaws, the former having holes 17 for bearings on the pivot pin or rivet 18, which is secured in the open-

ing 18' of the stationary jaws, and in Figure 2 the relation of the teeth 10 and 16 will be apparent. In full lines in this figure the teeth are separated, while in dotted lines 5 the tooth 16 is shown in gripping position for co-action with the tooth 10.

The pivotal movement of the gripping jaws is accomplished through a connection at the ear 19 of a bent link 20 one of which 10 is provided for each movable jaw. These links are pivoted to the arms 3 and 4 of the plier handles in holes 21 and through their connection to the perforated ears 19 of the movable gripping jaws, actuate said jaws 15 when the handles are pressed together. The gripping jaws are held in open position by connecting to the top perforated ears 22 thereon the respective springs 23 which springs are anchored at their other ends to 20 the perforated, bent end 24 of the links, which ends also form the pivot point for the links and connect them with the angle arms of the handles.

Thus it will be apparent that the jaws are 25 positively actuated to grip the ring and are released by tension of their springs, and that the arms are separated laterally to spread the ring ends by positive movement and returned, after release, to normal position by 30 the spring 11. In gripping the ring ends as before stated the teeth of the jaws engage only the outer edges of the ring ends, and it will be apparent that after the ring has 35 been expanded and slipped over the piston the ring may be permitted to snap into its groove. This positioning of the teeth prevents their contact with the piston and the inner edges of the ring ends are thus free 40 to slip into the piston groove without obstruction from the tool or implement. With the implement in full line position in Figure 1, the handles are pressed together by hand and the initial movement of the handles causes the pivoted gripping jaws to 45 grip the ring ends, through the link connection. The continued movement of the handles retains the grip on the ring ends and at the same time, through the link connection with the gripping jaws (which latter 50 carry the stationary jaws) the two members

of each gripping device are swung laterally and outwardly on the common pivot point 5 for the arms 6 and 7. When the dotted position of Figure 1 is reached the ring is slipped over the piston and placed in position for snapping into its groove. Upon releasing the handles 1 and 2 the grip on the ring ends is loosened and the spreading arms 6 and 7 are released thus permitting the expanded ring to contract and snap into its 60 groove. The several springs of the tool return the operating parts thereof to normal position for future use.

Having thus fully described my invention, what I claim as new and desire to secure by Letters Patent is—

1. The combination with a pair of pivoted handles having angularly disposed integral arms and a pair of spreader arms pivoted with said handles, of stationary jaws carried by said spreader arms, gripping jaws pivoted on said stationary jaws and laterally movable with the spreader arms, and pivoted links connecting said gripping jaws and angular arms.

2. The combination with a pair of handles having angularly disposed integral arms and a pair of spreader arms and a single pivot for the handles and spreader arms, of a pair of stationary jaws carried by said spreader arms and a spring connecting said jaws, gripping jaws pivoted on said stationary jaws and laterally movable with the spreader arms, pivoted links connecting said gripping jaws and angular arms, and retracting springs connecting said gripping jaws with remote ends of said links.

3. The combination with a pair of pivoted handles having angularly disposed integral arms and a pair of spreader arms pivoted with said handles, of stationary jaws carried by said spreader arms and a gripping tooth on each jaw, gripping jaws pivoted on said stationary jaws and a gripping tooth on each gripping jaw, and pivoted links connecting said gripping jaws and angular arms.

In testimony whereof I affix my signature.

THOMAS A. HUTSELL.
